Primary Examiner—Antoine D Davis

(74) Attorney, Agent, or Firm—Pillsbury Winthrop Shaw Pittman LLP

(57) **CLAIM**

The ornamental design for a tape rule hook, as shown and described.

DESCRIPTION

FIG. 1 is an isometric view according to my design;
FIG. 2 is a front plan view of the design of FIG. 1;
FIG. 3 is a rear plan view of the design of FIG. 1;
FIG. 4 is a right plan view of the design of FIG. 1;
FIG. 5 is a left plan view of the design of FIG. 1;
FIG. 6 is a top plan view of the design of FIG. 1; and,
FIG. 7 is a bottom plan view of the design of FIG. 1.
Where included, broken lines showing environment or structure are for illustrative purposes only and form no part of the claimed design.

1 Claim, 4 Drawing Sheets**US D617,224 S**
